UNITED STATES PATENT OFFICE

93,104

DESIGN FOR A COVER FOR HEATING RADIATORS

Edmund Hofmann, Chicago, Ill., assignor to
Herbert H. Krueger, Chicago, Ill.

Application July 5, 1934, Serial No. 52,466

Term of patent 7 years

To all whom it may concern.

Be it known that I, EDMUND HOFMANN, a citizen of the United States, residing at Chicago, in the county of Cook and State of Illinois, have invented a new, original, and ornamental Design for a Cover for Heating Radiators, of which the following is a specification, reference being had to the accompanying drawing, forming part

thereof and wherein Fig. 1 is a perspective view of a cover for heating radiators, showing my new design, and Fig. 2 is a fragmentary view in front elevation, of the same.

I claim:

The ornamental design for a cover for heating radiators, as shown.

EDMUND HOFMANN.
